Brown, Jackson, Bottcher & Dieruss
Attnys,

three conductors, with their rigidly anchored bushings in transverse alignment, are slightly elevated and the lower half of the insulator is slipped thereunder and properly positioned. Thereafter, the upper half of the insulator structure is applied and the locking rings are affixed to the two halves of the insulator structure, thereby locking the three conductors in the insulator structure.

The distance between insulators is always such as is found desirable or necessary in order to prevent the conductors from bowing or sagging so that these insulators maintain the conductors in insulated relation not only with respect to each other but also with respect to the metallic tubular structure forming a chamber thereabout.

When a suitable length of tubular conduit has been fabricated with the portions 34 and 33 standing upwardly in the trench and the conductors and insulators are included therein, the portions are caused to approach each other until the offset portion 36 of portion 34 laps the free edge portion or tongue 35. Then a suitable welded or soldered joint is effected between these two portions forming a leak-proof longitudinal seam in the tubular structure. Successive lengths of this tubular structure at their adjacent ends may be suitably secured together in leak-proof relation or special joint connections of leak-proof character may be provided if found desirable or necessary.

Referring to a section of conduit between manholes, such a section is then subjected to suction to exhaust the moisture and as much air as possible therefrom. Following such exhaustion the insulating liquid is supplied to the tubular conduit and the same is then observed for leakage along the joint represented by the portions 35-36 and at the joints between sections of the tubular conduit. All leaks, when discovered, are repaired. Following the aforesaid, the sections are tested for their insulated relation as between conductors included in the primary and tubular conduit.

It will be noted, see Fig. 2, that the entire tubular conduit, except for the conductors which are of bare character and the insulators, is entirely filled with the insulating liquid. This may be what is known as transformer oil or may be purified gasoline, the latter, as previously stated, having a high value so far as insulating properties are concerned. Upon satisfactory testing relative to leakage and electrical insulating the asphaltic mixture 23 is applied as shown in Fig. 2. Then the transmission line is ready for use.

It will, therefore, be readily apparent that the liquid in any length of conduit has free communication through the openings 46, as well as above the insulators and below the cover portions 33 and 34 and between the insulators, more particularly the portions 40 thereof and the bottom 38 of the primary conduit. With this construction, the liquid may be maintained in the primary conduit under pressure conditions, thereby insuring that the entire conduit is completely filled from one end of a section to the other or, in other words, from one manhole to another.

The connections between the tubes 19 and 20 with the tubular conduit are not illustrated herein. They, together with the equipment required, are a separate invention.

It will be observed, see Figs. 1 and 2, that the portions 33 and 34 form a slight arch in

cross-section which is sufficient to support the asphaltic material 23 thereabove since such arch tends to resist collapse toward the insulator. As previously stated, the insulators are of form 5 maintaining character with respect to the tubular conduit.

In Fig. 3 there is illustrated a modified form of the invention and the letters A, B and C indicate three bare wire conductors. D indicates 10 the split bushings rigidly mounted on said conductors. These are similar to those previously described and as illustrated in Figs. 1 and 2. The insulator in this embodiment of the invention includes a main body portion 60 which is 15 enlarged transversely at the ends as indicated at 61. These enlargements are of substantially semi-circular form having the curved surface 62, the space between the two and below the body portion 60 being designated by letter E. Extending downwardly from the top of the body portion 60 are the three parallel slots 62, each of which terminates in a semi-cylindrical bottom portion 63. The tubular portion of the split bushing D seats in this semi-cylindrical surface. The flange portions at opposite ends of each bushing straddle the side faces of the body portion 60. Thus, the insulator is rigidly associated with the several wires A, B and C. As shown herein, 64 indicates passages through the insulator between the slots 62 to provide for longitudinal communication as aforesaid. The portions 61, 62 at each upper end extend upwardly of the body portion 60 as illustrated, and thus the conduit form maintaining character of the insulator structure is provided for.

Since gravity operates on the wires at all times, it will be apparent that this type of insulator can be used in substantially all instances except at the bottom of a curve in the conduit when the form shown in Figs. 1 and 2, preferably, should be used in order to prevent contraction in the wires incident to change of temperature, that is in cold weather, elevating the wires sufficiently in or even out of the open slots 62 of the insulator shown in Fig. 3, thus permitting the wires to engage the portions 33 and 34 of the tubular primary conduit and short circuit. For all normal installations, therefore, the form of the insulator shown in Fig. 3 is equally as efficient as that shown in Figs. 1 and 2. That shown in Figs. 1 and 2, preferably, is employed over that shown in Fig. 3 in all the "dip" portions of the transmission line arrangement.

It will also be obvious with reference to Fig. 3 that the wires and insulator shown therein are mounted in a tubular conduit substantially similar or identical to that shown in Figs. 1 and 2 and that this tubular insulation structure is filled with insulating liquid and maintained in that condition, as previously described, and the same can be mounted in the underground conduit or tunnel, as shown in Fig. 2.

While the invention has been illustrated and described in great detail in the foregoing description, the same is to be considered as illustrative and not restrictive in character.

The several modifications described herein, as well as others which will readily suggest themselves to persons skilled in this art, are all considered to be within the broad scope of the invention, reference being had to the appended claims.

The invention claimed is:

1. In a high tension fluid insulated transmission system, the combination with an except-

tionally elongated metallic member initially arranged in open trough formation with upwardly directed side portions adapted for subsequent lateral and inward movement towards each other for top closure formation and to form a conduit of leakproof character, and a plurality of similarly elongated current conductors laterally presentable to the conduit before the closure thereof is effected, of a plurality of electrical insulating type mechanical spacing means laterally presentable to the conduit before the closure thereof and laterally mountable simultaneously upon the conduit included conductors and arranged at frequent intervals thereon and in the conduit, each spacing means substantially embracing the conductors and extending transversely across the conduit and engaging the opposite interior surfaces of the side portions for conduit form maintenance and conduit chamber formation between adjacent spacing means, said spacing means having a formation providing substantially free fluid communication between adjacent resulting conduit chambers, each spacing means having sockets such that when said means is mounted on the conductors the latter are spaced apart and spaced from the conduit, and other means laterally and rigidly mounted upon the conductor and cooperating with said insulating spacing means for preventing longitudi-

nal movement of said spacing means upon the conductors.

2. A system as defined by claim 1, characterized by each insulation spacing means being of two-part character, each part providing a partial socket for reception of each conductor and each laterally presentable to the conductors, confronting partial sockets forming the sockets for enveloping the conductors, said sockets having contact with the last mentioned preventing means and at opposite ends thereof.

3. A system as defined by claim 1, characterized by each insulation spacing means being of two-part character, each part providing a partial socket for reception of each conductor and each laterally presentable to the conductors, confronting partial sockets forming the sockets for enveloping the conductors, said sockets having contact with the last mentioned preventing means and at opposite ends thereof, and a connector for securing said parts together and positioned immediately adjacent the preventing means end contact with said parts, said parts including projections constituting continuations of the sockets, said projections including a peripheral groove, and the connector comprising a split clip ring laterally seatable in the conductor enveloping groove.
